SUBMARINE MINE.

1,231,950.

Specification of Letters Patent.

Patented July 3, 1917.

Application filed July 31, 1915. Serial No. 42,947.

To all whom it may concern:

Be it known that I, JOSEPH AIMÉ SENG, of 17 Avenue de La Bourdonnais, Paris, France, engineer, have invented a new and 5 useful Improvement in Submarine Mines, which improvement is fully set forth in the following specification.

This invention relates to submarine mines provided with mechanism adapted to operate after an interval, such mines being particularly applicable for submarine boats.

This invention allows this result to be obtained by a time apparatus which is particularly applicable for anchoring submarine 15 mines.

A member which is intended to move after a certain interval is normally locked by any suitable mechanism. The time apparatus which serves to unlock that member is contained in a water tight casing which may also contain the said member. Means are provided by which water can be admitted into the casing to act upon a soluble locking stop or pin to allow mechanism to operate to 25 unlock the member.

The soluble pin may normally retain either the lock itself or a part acting upon the lock.

Means may be provided to prevent the 30 disengagement of the lock on the breakage or premature destruction of the pin.

In the accompanying drawing Figure 1 is a vertical section of an anchor of a submarine mine, Fig. 2 is a similar view of a 35 modification and Fig. 3 is a perspective detail view of part of Fig. 1.

In the drawings *a* is the mooring drum of a submarine mine normally locked by a catch *b* pivoted at *b'* which engages teeth *c* on the 40 periphery of the drum.

In Fig. 1 the time apparatus is contained in an anchor *d* which incloses the drum *a*, the anchor being rendered water tight at the point *d'* through which the mooring rope 45 passes.

e is a cock provided with a passage *f* which connects the inside of the anchor with the outside by a passage *g*. A spring *h* tends to remove the catch *b* from the teeth 50 of the drum but is prevented from so doing by a soluble pin *i*, formed of ammonium chlorid, for example, which normally retains the catch in engagement. If the cock *e* is opened and the anchor with its mine is 55 in the water, water passes into the interior

of the anchor, dissolves the pin *i* and the spring *h* causes the catch *b* to move out of engagement with the teeth *c* thus releasing the drum.

Preferably the cock *e* is provided with a 60 tail *j* bifurcated at *j'* with which the end of the catch *b* will engage if liberated by the premature destruction or accidental breakage of the pin *i*.

The end of the catch would at the same 65 time enter the groove of a projection *k* on the frame of the anchor. The cock *e* will thus be rendered immovable.

In Fig. 2 the time apparatus is contained in a separate water tight vessel *l* closed by a 70 cock *e* provided with a passage *g*. Inside the vessel *l* is a piston *m* which a spring *n* constantly tends to push upward and which is provided with a rod *o*. *p* is a soluble pin which normally maintains the rod in its 75 down position. If the cock *e* is opened, water passes into the vessel and dissolves the pin *p*, the rod under the action of the spring *n* moves upward into the passage *g* of the cock and removes the catch from the 80 teeth *c* thus liberating the drum.

For security the rod *o* is preferably provided with a stem *q* and the cock *e* with an opening *r* which, when the cock is closed, is 85 opposite the stem *q*.

If the pin dissolves prematurely or breaks accidentally, the rod is set free and its stem *q* engages the opening *r* and retains the cock *e* and immobilizes the apparatus. While the stem *q*, when the pin *p* has been prematurely 90 broken or dissolved, will thus prevent the operation of the cock *e* by the application of ordinary force thereto, it will be apparent that by the application of increased force to the cock it may be turned, wrenching the reduced stem *q* from the body of the rod *o*. Thereupon water will be admitted to the vessel *l* whereby the anchor and mine will sink; but stem *q* being broken, catch *b* will not be actuated to release the drum *a* because 95 rod *o* although entering passage *g* cannot reach the catch. It will also be apparent that the same result may be accomplished with the structure of the modification of Figs. 1 and 3 in any suitable way.

105

Claims:

1. In a submarine mine, the combination with a water-tight casing, of means to admit water thereto, locking means, lock-disengaging means, a soluble stop inside said casing 110

to restrain said lock-disengaging means, and means to restrain said lock-disengaging means upon a premature failure of said stop.

2. In a submarine mine, the combination 5 with a water-tight casing, of means to admit water thereto, locking means, lock-disengaging means, a soluble stop inside said casing to restrain said lock-disengaging means, and means to restrain said lock-dis-

10 engaging means and said water-admitting means upon a premature failure of said stop.

3. In a submarine mine, the combination 15 of locking means, lock-disengaging means, a water-tight casing, a soluble stop inside the casing adapted to restrain said lock-disengaging means, means for admitting water into said casing, and means for preventing the operation of said lock-disengaging means when said means for admit-

20 ting water is in closed position.

4. In a submarine mine, the combination 25 of locking means, lock-disengaging means, a water-tight casing, a soluble stop inside the casing adapted to restrain said lock- disengaging means, means for admitting wa- 30 ter into said casing, and means for pre- venting the operation of said lock-disengag- ing means when said means for admitting water is in closed position, said last-named means preventing the operation of said 35 means for admitting water on the premature removal of said soluble stop.

5. In a submarine mine the combination 35 of a locking catch, a spring tending to dis- engage the catch, a water tight casing, a soluble stop inside the casing adapted to prevent the spring from operating, a cock for admitting water into the casing, and means for preventing said spring from op- 40 erating the catch when the cock is in its closed position.

6. In a submarine mine the combination 45 of a locking catch, a spring tending to dis-

engage the catch, a water tight casing, a soluble stop inside the casing adapted to prevent the spring from operating, a cock for admitting water into the casing and means for preventing said spring from operating the catch when the cock is in its closed position, which means also prevent the movement of the cock on the premature removal of the soluble stop.

7. In a submarine mine, the combination 50 of locking means, lock-disengaging means, a water-tight casing, a soluble stop inside the casing adapted to restrain said lock-disengaging means, means for admitting water into said casing, and means for preventing the operation of said lock-disengaging means when said means for admitting water is in 55 closed position, said last-named means preventing the operation of said means for admitting water on the premature removal of said soluble stop except by the application of increased force to said water-admitting means.

8. In a submarine mine, the combination 60 of a locking catch, a spring tending to dis- engage the catch, a water-tight casing, a soluble stop inside the casing adapted to prevent the spring from operating, a cock for admitting water into the casing, and means for preventing said spring from op- 65 erating the catch when the cock is in its closed position, which means also prevent the movement of the cock on the premature removal of the soluble stop except by the application of increased force to said cock.

In testimony whereof I have signed this 70 specification in the presence of two subscrib- 75 ing witnesses.

JOSEPH AIMÉ SENG.
